UNITED STATES PATENT OFFICE.

ADOLPH MENGES, OF NEW YORK, N. Y.

DESIGN FOR TRIMMING.

SPECIFICATION forming part of Design No. 15,149, dated July 15, 1884.

Application filed May 23, 1884. Term of patent 7 years.

To all whom it may concern:

Be it known that I, ADOLPH MENGES, of the city of New York, in the county and State of New York, have invented and designed a new and original Chenille Trimming, of which the following specification is a full, clear, and exact description.

The drawing represents a side view of my newly-designed chenille trimming.

10 The letters A A represent the several lengths of chenille connected at one end to form a trimming. Each length A is composed of a small ball, a, at one end, a larger ball, b, at the other

end, and an intermediate portion, c, which is thinner and longer than balls a b, and terminates in a tuft, d, as shown. The sections a b c are separated by a cord, e, which is also above and below balls a b.

I claim as my design—

The design for chenille trimming, consisting of balls a b, section c, having tufted portion d, and cord e, as described and shown.

ADOLPH MENGES.
